(57) **CLAIM**

The ornamental design for a display screen with user interface, as shown and described.

DESCRIPTION

FIG. 1 is a front view of a display screen with user interface showing our new design; and,
FIG. 2 is a front view of the display screen of FIG. 1 shown on a device.

The broken line showing of the remainder of the display screen in FIGS. 1 and 2, various icons in FIGS. 1 and 2, and the device having the display screen with user interface in FIG. 2 illustrates unclaimed environment and forms no part of the claimed design.

1 Claim, 2 Drawing Sheets

FIG.

FIG. 2
